UNITED STATES PATENT OFFICE.

HENRY E. LEPPERT, OF NEW BRITAIN, CONNECTICUT, ASSIGNOR TO THE TRUMBULL ELECTRIC MANUFACTURING COMPANY, OF PLAINVILLE, CONNECTICUT, A CORPORATION OF CONNECTICUT.

KNIFE-BLADE SWITCH.

Application filed October 6, 1924. Serial No. 741,787.

To all whom it may concern:

Be it known that I, HENRY E. LEPPERT, a citizen of the United States of America, residing at New Britain, Hartford County, 5 State of Connecticut, have invented a new and useful Knife-Blade Switch, of which the following is a specification.

My invention relates particularly to quick-break switches of the so-called safety 10 type. Such constructions frequently have hinged blades mounted upon an insulating base of slate or porcelain and are provided with a handle for manual operation and mechanism for making and breaking a circuit with a snap action out of the control 15 of the operator. When such switches are operated there is an essential shock and jar which tends not only to loosen the parts but sometimes even to break them.

20 The main object of my invention is to prevent such injury. Specifically I have sought to provide a simple and inexpensive construction embodying switch jaws having a buffer which can be readily applied to 25 standard type switches.

Another object is to provide a form of buffer which can be readily replaced or renewed.

20 The accompanying single sheet drawing illustrates the preferred form of my invention and also some modifications.

Figure 1 is a perspective view of a safety switch construction embodying one form of the invention.

35 Figure 2 is a fragmentary side view and partial section of the principal parts of the construction.

40 Figure 3 is a fragmentary end view looking at the construction shown in Figure 2 from the left.

Figure 4 is a perspective view showing the various parts of a switch jaw and buffer separated.

45 Figures 5 and 6 are side views showing different ways of securing a buffer to a switch jaw.

In the standard type construction illustrated, there is a stationary post 10, stationary spring jaws 11, and a blade 12 hinged to the post 10 and adapted to engage between the jaws 11. These parts are usually supported by an insulating base 13 formed of slate or porcelain.

The switch mechanism per se is mounted

in a suitable manner in some form of box 55 or receptacle 14 usually of steel. The invention is applicable to a switch having any number of blades. In the form shown the operating crank 15 is pivotally supported in the box and provided with an external 60 operating handle 16. The operating crank 15 is connected to the switch blades in any suitable manner, as for instance by a hook-like member 17, an insulating crossbar 18, and brackets 19. A quick-break spring 65 mechanism 20 is connected to the operating crank 15 in any suitable manner for accelerating the opening and closing movement in any well known or satisfactory manner.

A buffer 21 is secured to the jaw member 70 11 in a position to receive the impact of the knife blade 12 in its circuit closing movement. This buffer is preferably formed of

hard fibre or similar material with its grain 75 running transversely to the knife blade so that the shock of the blade and attached parts will not be likely to split or chip it.

This buffer is secured to the jaw member 11 for instance by means of a member 22 which extends into the buffer member and 80 is locked to the jaw member. One end of the member 22 may have teeth 23 so that

it may be readily driven into the buffer but will not accidentally work loose. The other end is secured to the jaw member, for 85

instance by means of a pin or rivet 24 which extends through the opening 25 of the jaw member and interlocks in a notch 26 in the connector 22. The parts are so shaped and proportioned that when assembled the 90

buffer rests on the base 13 and against the edge of the jaw member 11 and its foot 27, as shown in Figure 2. The jaw member is secured to the base 13 in the usual manner, for instance by one or more screws 28. The 95

parts may be proportioned so that the buffer receives the impact not only of the blade 12 but of the bracket 19 so that the shock and strain are more widely distributed and therefore less likely to injure the buffer or 100 base.

Should the buffer be broken or become worn it is a very simple matter to remove the pin 24 and insert a new buffer, the cost of which is insignificant. Should the jaws become worn or injured a new set 105 with a fresh buffer attached can be readily substituted.

In the form shown in Figure 5 the buffer

is secured to the jaw member by an ordinary screw 30 whose head fits against the edges of the jaw member to hold it in place.

In the form shown in Figure 6 the buffer 5 is connected to the jaw member by means of a staple 32 and the pin 24.

The member 22, or whatever other form of holding member may be substituted therefor, is preferably a little less in thickness 10 than the space between the jaw blades so that the necessary spring of the jaws is not affected by the addition of the buffer member. Also the parts are so proportioned that the buffer member has a slight freedom of 15 movement so that the full impact of the knife blade 12 against the buffer member is not transmitted to the jaws.

Obviously this construction permits the contact jaw member 11 and its base 27 and 20 the buffer 21 to be assembled and sold as a unit which is of considerable advantage to the trade. This feature also facilitates the factory assembly of the switch. A point of great importance is that the spring of the 25 jaws is not affected by any amount of battering or wearing of the buffer member.

It will be seen that this simple type of buffer construction is adapted to be readily applied to almost any type of knife blade 30 switch without requiring any material modifications in the standard blades and switch jaws. The use of such buffers not only materially prolongs the life of the switch but decreases the noise of operation.

35 I claim:

1. A knife switch contact including spaced contact jaws, a stop block member and link means loosely connecting said block member with said jaws to retain said block member 40 in fixed position adjacent said jaws but entirely outside of the space between said spaced jaws.

2. A knife switch including spaced contact jaws, a foot supporting said jaws, a stop 45 member for receiving the impact of a co-operating knife switch blade, and means for securing said stop member alongside said jaws and said foot, the said stop member being positioned outside of the space between 50 the said jaws so that the spreading of said stop member will not spread said jaws.

3. In a knife blade switch, a switch base, a hinge post and a contact jaw on said base, a switch blade pivoted to said hinge post, 55 and an insulating stop block mounted on said base between said hinge post and said

contact jaw and secured to one of said two latter members to retain said stop block in substantially fixed position.

4. In a knife switch, a switch base, a hinge jaw and a divided contact jaw mounted on said base, a switch blade pivoted to the hinge jaw and a fibrous buffer block to receive the closing impact of said switch blade, the said buffer block being mounted 60 on the surface of the base adjacent to said contact jaw and having an anchor member connecting said buffer block with said contact jaw to retain said buffer block in position so that the spreading of said block 70 will not spread said jaw.

5. In a knife switch contact, yielding switch jaws spaced apart, an anchor member secured to said jaws and a fibre stop block secured to said anchor member, the 75 said stop block being positioned to receive the impact of a co-operating switch blade without spreading said jaws and said anchor member being positioned to be entirely clear 80 of the path of movement of the said switch blade.

6. In a knife blade switch, spaced jaw members adapted to receive the knife blade of the switch, a nonmetallic buffer member and a connector having teeth secured in 85 said buffer member, and having a shank secured between said jaw members.

7. In a knife blade switch, a switch base, a pivoted switch blade mounted on said base, a contact member mounted on said 90 base and having contact jaws spaced apart and a buffer member secured to said jaws and supported directly upon said base and being positioned in line with the space between 95 said contact jaws and entirely outside of said space.

8. In a knife switch contact, a pair of yielding jaws, a buffer member outside but adjacent the edge of said jaws, a connector having one end secured in said buffer and 100 the other end extending between said jaws and rivet means for securing said connector to said jaw members.

9. In a knife switch contact, a pair of yielding jaws, a buffer member closely adjacent the edges of said jaws, a connector secured to said buffer and extending between 105 said jaws and means extending through said jaws for securing the parts together as a unit.

HENRY E. LEPPERT.
